UNITED STATES PATENT OFFICE.

AARON T. HOYLE, OF CASAR, NORTH CAROLINA.

NUT-LOCK.

1,252,441.

Specification of Letters Patent.

Patented Jan. 8, 1918.

Application filed March 27, 1917. Serial No. 157,690.

To all whom it may concern:

Be it known that I, AARON T. HOYLE, a citizen of the United States, residing at Casar, in the county of Cleveland and State 5 of North Carolina, have invented certain new and useful Improvements in Nut-Locks; and I do hereby declare the following to be a full, clear, and exact description of the invention, such as will enable others 10 skilled in the art to which it appertains to make and use the same.

This invention has for its object to provide an improved nut lock in which the nut is held against rotary movement upon the 15 bolt by a locking element slidably and non-rotatably associated with the bolt.

Another object is the provision of a nut lock including a contractible locking element, which is contracted during advance of 20 the nut to firmly grip the bolt and positively insure against any loose movement whatever between the nut and bolt.

With these and other objects in view, the invention consists in the novel construction, 25 combination and arrangement of parts as will be hereinafter more fully described, claimed and illustrated in the accompanying drawing, in which:

Figure 1 represents a side elevation of the 30 improved nut lock applied to use,

Fig. 2 represents a longitudinal sectional view through the nut lock, the bolt being shown in side elevation,

Fig. 3 represents a transverse sectional 35 view on the line 3—3 of Fig. 1,

Fig. 4 represents a transverse sectional view on the line 4—4 of Fig. 1,

Fig. 5 represents a longitudinal sectional 40 view through the nut detached, and Fig. 6 represents a side elevation of the locking element removed from the bolt.

Referring to the drawing in detail, wherein similar reference numerals designate corresponding parts throughout the several 45 views, the numeral 5 indicates an ordinary type of bolt having the usual external screw threads extending inwardly from one end and a head 6 at the opposite end. The bolt 5 is cut away longitudinally to present a 50 longitudinal flat surface 7, adapted to co-operate with the corresponding flat surface formed internally of the locking element, designated generally by the numeral 9, to secure the latter against rotary movement 55 upon the bolt.

The locking element 9 is in the form of a

ring or sleeve, and is preferably formed of spring metal. The ring or sleeve is formed with a longitudinal slit 10, permitting it to be freely moved longitudinally of the bolt 60 7. One end of the locking element is tapered, as indicated at 11, and the relatively large cylindrical portion thereof is formed with closely arranged longitudinal 65 grooves 12.

A nut 13, having a longitudinal bore 14, is positioned upon the bolt 5 outwardly of the locking element 9, and the inner part of the nut is of cylindrical formation, while the outer part thereof is cut away to provide 70 a series of wrench-engaging faces 15. One terminal of the internal bore 14 of the nut is screw threaded, as indicated at 16, to co-operate with the external screw threads of the bolt 5, and the central portion of the 75 bore is increased in diameter or flared, as at 17, the inclination of the flared portion 17 approximately corresponding to the inclination of the tapered terminal 11 of the locking element. The end of the bore 14 opposite the threaded portion 16 is plane and cylindrical, as indicated at 18, and is of such diameter as to receive the grooved portion 12 of the locking element. A locking screw 19 is fitted in the wall of the cylindrical portion 18 of the bore in the nut and is provided with a pointed terminal for engaging in one of the several grooves 12 to establish a non-rotatable connection between the locking element and nut. 80 90

In use, the locking element 9 is slipped upon the bolt 5 and moved longitudinally thereon against an object 21, the locking element being securely held against rotary movement with relation to the bolt by the 95 flat internal face 8 thereof engaging the straight flat face 7 of the bolt. The screw 19 is subsequently adjusted so that the inner pointed terminal thereof is moved outside of the plane of the plane cylindrical portion 18 of the internal bore of the nut, permitting the latter to be advanced toward the object 21 until the inclined surface 17 of the bore overlies and compresses the tapered terminal of the locking element 9, 105 thereby contracting the latter and firmly clamping it upon the bolt. By contracting the locking element in the manner described, it is evident that it is firmly clamped about the bolt preventing loose movement of the 110 locking element with relation to the bolt. Subsequent to the proper adjustment of the

nut, the screw 19 is advanced and the inner pointed terminal thereof enters one of the grooves 12 in the locking element, thereby establishing a non-rotatable connection between the nut and locking element and effectively preventing accidental removal or loosening of the nut from the bolt.

What I claim is:

1. A nut lock including a bolt, a contractible locking element slidably and non-rotatably mounted upon the bolt, a nut capable of contracting the locking element upon the bolt, and adjustable means for securing the nut against rotary movement with relation to the locking element.
2. A nut lock including a bolt, a contractible locking element slidably and non-rotatably mounted upon the bolt, and a nut fitted upon the bolt capable of contracting the locking element to firmly clamp the latter upon the bolt.
3. A nut lock including a bolt, a locking element slidably and non-rotatably mounted upon the bolt having a tapered terminal, and a nut fitted upon the bolt having the inner terminal of the bore flared to receive and compress or contract the locking element upon the bolt.
4. A nut lock including a bolt, a contractible locking element slidably and non-rotatably mounted upon the bolt having a tapered outer terminal, a nut fitted upon the bolt having the inner terminal of the bore flared and adapted to coöperate with the tapered terminal of the locking element to contract the latter upon the bolt, and a screw fitted in the inner terminal of the nut adapted to engage the locking element to secure the nut and locking element against rotary movement.

5. A nut lock including a bolt, a ring-like locking element slidably and non-rotatably mounted upon the bolt having a tapered outer terminal and a longitudinally grooved body portion, a nut fitted upon the bolt having the inner terminal of the bore thereof flared and adapted to coöperate with the tapered terminal of the locking element to contract the latter about the bolt, and adjustable means carried by the nut for engaging in the grooves of the locking element to secure the nut against rotary movement with relation thereto.

In testimony whereof I affix my signature in presence of two witnesses.

AARON T. HOYLE.
